UNITED STATES PATENT OFFICE.

CHARLES E. BENTLEY, OF NEW YORK, N. Y.

DESIGN FOR A PILLOW-TOP.

SPECIFICATION forming part of Design No. 35,596, dated January 21, 1902.

Application filed November 18, 1901. Serial No. 82,790. Term of patent 3½ years.

To all whom it may concern:

Be it known that I, CHARLES E. BENTLEY, a citizen of the United States of America, and a resident of the borough of Manhattan, city of New York, State of New York, have invented and produced a new and original Design for a Pillow-Top, of which the following is a specification, reference being had to the accompanying drawing, forming part thereof, and which is a plan view of a pillow-top illustrating my design.

This design comprises a centerpiece or field representing a blooming wild rose 1 and a foliated marginal portion having the outline of a series of leaf-like tabs 2, which radiate from the central rose and taper outward at the edges toward their point or outer end.

A minor feature of the design comprises a border or band 3, extending along the edge of each radial tab from its base to its point. 20

The more essential feature of the design is the central representation of a wild rose surrounded by radiating and tapering leaf-like tabs forming a foliated margin to the wild-rose centerpiece. 25

I claim as my invention—

The design for a pillow-top, substantially as herein shown and described.

CHARLES E. BENTLEY.
